X-RAY TUBE AND CATHODE THEREFOR

Clayton Tridle Ulrey, East Orange, N. J., assignor
to Westinghouse Lamp Company, a corpora-
tion of Pennsylvania

Application March 28, 1933, Serial No. 663,107

5 Claims. (Cl. 250—35)

This invention relates to electric discharge devices and more particularly devices of this character adapted to be employed for the production of X-rays and commonly termed X-ray tubes.

5 In its more specific aspect the invention is directed to improved means adapted to produce a focal spot on the anode target of a tube of this character. Heretofore X-ray tubes containing an anode and a cathode within an evacuated envelope have been employed in a number of different fields, including the therapeutic, radiographic and industrial fields. X-ray tubes employed in these fields have contained cathode structures of one type or another.

10 15 Prior to the time of this invention it has been proposed to employ a cathode structure consisting of a cup in which is mounted a spirally wound filament through the center of which extends an elongated thin pin adapted to deflect the electrons which emanate from the filament.

20 25 In the course of my experimentations with cathode structures of the above noted character, and especially such structures when employed in X-ray tubes, I have found that with such a cathode structure the focal spot produced on the target of an X-ray tube consists of an annular spot with a spot of appreciable area at the center thereof. The spot in the center of the annular spot was objectionable.

30 35 In order that I might overcome the difficulties inherent in the heretofore employed cathode structures and especially those employed in X-ray tubes I have developed the following invention, which will hereinafter be more fully disclosed.

An object of my invention is to provide an X-ray tube having advantages over those now employed.

Another object of my invention is to provide 40 a new type of cathode structure.

Another object of my invention is to provide an improved cathode for obtaining an annular focal spot with no spot in the center thereof.

45 Other objects and advantages of my invention will be readily apparent from the following description and drawing wherein;

Figure 1 illustrates a shortened fragmentary view with some of the parts in elevation and others in cross section of an X-ray tube embodying my invention;

Figure 2 represents a cross sectional view taken along lines II—II of Figure 1;

Figure 3 represents a cross sectional view showing the improved cathode structure as mounted

and the relationship of the different parts to the cathode structure;

Figure 4 represents a plan view of the cathode structure taken in the direction of the large end of the cathode cup;

5 Figure 5 represents the focal spot obtained by employing the structure shown in Figure 1;

Figure 6 represents the focal spot obtained by employing a modified focusing cup having no cutouts and employed in the position shown in 10 Figure 1.

Figures 7 and 8 represent the type of focal spots obtained with some prior art cathode structures.

As shown the X-ray tube comprises a vitreous dielectric envelope 10 in which is located an anode 11 having a target 12 composed of tungsten or the like and embedded in the free end thereof. The face of said target 12 is located in a plane that makes an angle of about 45° with the longitudinal axis of the anode. Surrounding the free end of 20 said anode and also located within the envelope is a nickel-iron screen 13 adapted to prevent scattered electrons from striking on the inner walls of the envelope and/or to screen out undesirable X-rays and to house the novel cathode 25 structure 14.

The screen consists primarily of a cylindrical member 15 having a plurality of depressions or grooves adapted to accommodate the heads of 30 spring members 18. The upper end of said cylinder has a circumferential slot in which is set an annular plate 16 of predetermined dimensions. This plate is of the same thickness and composition as said cylinder and is secured to said cylinder by means of pins or the like.

The annular plate 16 has a central opening 17 through which some of the X-rays generated at the anode may travel unobstructed to the envelope and therethrough to the outer atmosphere. The cylindrical member 15 has a circumferential slot on the outer portion thereof and located near its bottom edge. Located in this slot is a spring wire and also located in said slot below said spring wire are the respective edges of the spring members 18, which bear against 40 the outer surface of the cylindrical member and against the inner surface of the envelope in order to maintain the screen against longitudinal movement.

Secured to said plate 16 is a metallic bushing 19 that is in electrical contact therewith. This bushing 19 is also electrically connected to a lead-in wire 23 which is hermetically sealed to the envelope and electrically connected to a contact terminal (not shown). Also secured to said plate 50 55

16 and located in an opening thereof is an insulating bushing 20. An electrical conducting lead wire 24 extends through an opening of said bushing 20 and has one end thereof like the lead wire 5 23 hermetically sealed to the envelope and connected to a contact terminal (not shown). The other end of said lead wire 24 is electrically connected to a cathode as hereinafter described.

The novel cathode structure 14 comprises 10 essentially a focusing cup in which is mounted a cathode associated with a cooling and deflecting pin and an electron shielding means. The focusing cup comprises a plurality of metallic cylinders 30 and 31 united to each other by a 15 flange 32, with the cylinder 30 having a diameter about one-half that of the cylinder 31. The outer end of the cylinder 31 has cut out portions 33 of small depth and about 1/4 of the depth of the cylinder 31 and whose lengths are about one-fourth the peripheral dimension of said cup 31. These cut out portions 33 are in opposite diametrical relationship.

20 Mounted in the small diameter cylinder 30 is a thermionic element or cathode 34 which may be composed of tungsten, tantalum or the like. This cathode 34 may be of filamentary form and of appropriate length and cross section to supply the necessary electron emission when heated to a predetermined temperature by means of a 25 source of potential (not shown).

The filamentary cathode 34 may consist of about seven and one-half turns and is spirally wound so that it simulates a cone made up of a plurality of spaced coils. One end of the filament, and as shown the end thereof at the base of the cone, is secured to the cup 30 so as to be in 30 electrical contact therewith. The other end of the filament at the apex of the cone extends along the altitude of the cone. A substantial length 35 of said filament extends along, is wound around and is in contact with substantially the entire length of the solid cooling and electron deflecting pin 35.

This pin 35 may be composed of molybdenum 40 and has a diameter about five times the corresponding dimension of the filament 34. The pin extends along the altitude of the cone and has one end located approximately in the space described by the topmost turn of the filament 34. 45 The cathode assembly consisting of the coiled filament 34 and the pin 35 is so mounted, with one end of the filament welded to the cylinder 30 and the pin 35 welded to a support and conductor 36, that the altitude of the cone 50 defined by the pin is substantially in the center of and coincident with the longitudinal axis of the focusing cup. The cone or coiled filament and pin are so located in said cup that the pin is substantially flush with the topmost coil of the cone and about 0.5 mm. above the top of the flange 32. Secured to the inner surface of 55 said cylinder 30 and with its upper portion located about 1 mm. below the top of the flange 32 is an annular ring of L shaped cross sectional configuration.

70 One side 37 thereof in the form of a ring is contiguous with the inner surface of the cylinder 30 and the other side 38 thereof is substantially perpendicular to the longitudinal axis of the cylinder 30. The side 38 is closely adjacent but not contacting the second turn of the filament 34 to substantially completely shield the last two turns of said filament so that the electrons emanating from these last two turns are prevented

from traveling through the cup and striking the anode.

The focusing cup is supported by the plate 16 and is electrically connected thereto by an angular metallic plate 39 welded to both the plate 16 and the flange 32. The conductor 36 secured to the pin 35 serves to aid in supporting the filament and permits current to pass thereto by virtue of its being connected also to the lead 24 and insulated from the plate 16.

10 This cathode structure as heretofore described may be assembled as shown with the mouth of the focusing cup being at a relatively small acute angle to the target face of the anode. With this construction it is possible to obtain an annular 15 focal spot with no center spot because the innermost turn or turn and a half of the filament are cooled so that the electron emission therefrom is materially less than that of the remaining portion of the filament, and because the outermost two turns or so of the filament are shielded by means of the shielding arm 38 to prevent the electrons emanating from these turns of the filament from reaching the anode. Thus 20 relatively none of the electrons that strike the target are derived from the first turn or the last two turns of the filament when a working potential is applied between the anode and cathode.

25 The invention is susceptible to modifications and the scope thereof is to be limited only by the prior art.

30 What is claimed:

1. An X-ray tube comprising an envelope, an anode and a cathode structure therein, said anode having a target disposed at an acute angle to the longitudinal axis of said envelope, an electron shield having an opening therein through which X-rays may emerge, said cathode structure being supported by said screening means which is located within said envelope, said cathode structure including a focusing cup and a spiral filament, said filament being located in said cup and having the apex thereof directed towards said target, a shielding means electrically connected to said focusing cup and located adjacent one turn of said filament for preventing the electrons emanating at said turn upon filament incandescence from reaching said anode.

2. An X-ray tube comprising an envelope, an anode, a cathode structure and an X-ray screening means located in said envelope, said X-ray screening means housing said cathode structure and that end of the anode carrying the target, said cathode structure being supported by said screening means and including a focusing means, a spiral filament and a cooling and deflecting pin, said spiral filament being in electrical series relationship with said focusing means and said pin, said pin extending along the altitude of said spiral filament, a shielding means supported by said focusing means and located between the face of the target and one turn of said filament to prevent the electrons emanating at that turn upon filament incandescence from striking the anode.

3. A cathode structure comprising a focusing cup and a filament located therein, said focusing cup including a plurality of concentric means, one of said means being of larger diameter than said other means and being connected to said other means, said filament having a portion thereof located in said other means, the outer limit of said means of larger diameter having a plurality of cut-outs therein.

4. A cathode structure comprising a focusing cup having a mouth, a spiral filament simulat-

- ing a cone and mounted therein and means electrically connected to said filament to shield one turn of said filament for preventing any substantial quantity of the electrons emanating at 5 said turn upon filament incandescence from traveling to the mouth of said cup, said one turn of said filament being located below said means, and a plurality of other turns of said filament located above said means.
- 10 5. A cathode structure comprising a focusing cup having a mouth, a spiral filament mounted therein, and having one end thereof connected to said cup, shielding means secured to the inner surface of said cup and being electrically connected thereto, said shielding means being closely 15 adjacent one turn of said filament for preventing any substantial quantity of electrons emanating at said turn upon filament incandescence from traveling to the mouth of the cup, said shielding means being located appreciably below the mouth of the cup and a cooling and deflecting pin extending along the altitude of said spiral filament, one end of said pin being located in the space described by the uppermost turn of said filament, said spiral filament simulating a cone said turn of said filament being located below said shielding means and some other of the turns of said filament being located above said shielding means.
